(57) **CLAIM**

The ornamental design of a drinking vessel, as shown and described.

DESCRIPTION

FIG. 1 is a top perspective view of a drinking vessel showing my new design;

FIG. 2 is a bottom perspective view of the drinking vessel of FIG. 1

FIG. 3 is a front elevated view of the drinking vessel of FIG. 1;

FIG. 4 is a rear elevated view of the drinking vessel of FIG. 1;

FIG. 5 is a left side elevated view of the drinking vessel of FIG. 1;

FIG. 6 is a rear elevated view of the drinking vessel of FIG. 1;

FIG. 7 is a top plan view of the drinking vessel of FIG. 1; and,

FIG. 8 is a bottom plan view of the drinking vessel of FIG. 1.

The broken lines in the drawings depict portions of the drinking vessel that form no part of the claimed design.

1 Claim, 7 Drawing Sheets
